CLAIM

The ornamental design for a female urinary collection and drainage device as shown and described.

DESCRIPTION

FIG. 1 is a top perspective view of a female urinary collection and drainage device in accordance with an embodiment of our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top perspective view of a female urinary collection and drainage device in accordance with an embodiment of our new design;

FIG. 10 is a bottom perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The dash dot lines immediately adjacent to the shaded areas in the view represent the boundaries of the claimed design. The dashed lines in the figures illustrate the portions of the design that form no part of the claimed design. None of the broken lines form any part of the claimed design.

1 Claim, 16 Drawing Sheets
